Patented Mar. 8, 1921.

UNITED STATES PATENT OFFICE.

ABRAHAM A. FAGEN, OF MINNEAPOLIS, MINNESOTA, ASSIGNOR OF ONE-HALF TO
HYMEN A. DIAMOND, OF MINNEAPOLIS, MINNESOTA.

WINDOW HEATER AND DRIER.

1,370,955.

Specification of Letters Patent.

Patented Mar. 8, 1921.

Application filed January 23, 1919. Serial No. 272,657.

To all whom it may concern:

Be it known that I, ABRAHAM A. FAGEN, a citizen of the United States, resident of Minneapolis, county of Hennepin, State of Minnesota, have invented certain new and useful Improvements in Window Heaters and Driers, of which the following is a specification.

In the operation of a vestibuled street car or motor bus conveyance, or any vehicle having a window or wind shield with glass panels in front of the driver, great difficulty is experienced in stormy weather because of the inability of the driver to see clearly through the glass any object or obstruction in the path of the vehicle. It sometimes happens in a snow or sleet storm that the glass in front of the driver will become so coated on the outside that his vision of the track is almost entirely obscured. This is true also of the driver of an automobile or motor bus. It also frequently happens in warm weather during a rain storm that drops of water will stand on the glass or condensation will accumulate on it to such an extent that other vehicles cannot be seen and accidents frequently happen.

The object, therefore, of my invention is to provide a device by means of which the glass panel of the window or wind shield may be heated in cold weather to remove the ice and snow and in warm weather to dry the moisture or condensation thereon.

The invention consists generally in various constructions and combinations, all as hereinafter described and particularly pointed out in the claims.

In the accompanying drawings forming part of this specification,

Figure 1 is a perspective view of the forward portion of a street car, showing my invention applied thereto,

Fig. 2 is an inside view of the sash supporting my invention,

Fig. 3 is a sectional view on the line 3—3 of Fig. 2,

Fig. 4 is a sectional view on the line 4—4 of Fig. 2,

Fig. 5 is a detail view, showing the preferred manner of mounting the heater and drier on the sash of the window.

In the drawing, 2 represents a street car of any ordinary or preferred construction. It is provided with the usual vestibule 3 and

a series of windows 4 through which the driver of the car may have a clear vision of the track ahead. These windows have preferably an upper and a lower sash, the upper one 5 being about the height of a man's head from the floor, so that as the driver stands by the control lever of the car he can look through the windows 5 without stooping merely by turning his head from side to side. The metal sash or the one through which the driver usually watches the track would be removed in stormy weather and in place thereof a sash 6 substituted, having a panel 7 of glass or other suitable transparent material. This sash would temporarily take the place of one of the sash 5.

A socket 8 for an electric circuit plug is mounted on the frame 6 and conductors 9 are secured to the frame 6 which preferably is of wood or other suitable nonconducting material, and extend partially around the frame and have an electric connection with a wire coil 10 which engages a hook 11 mounted on a plate 12 that is secured to the sash frame. A similar plate 12^a is secured to the opposite rail of the sash and carries a hook 11^a for engagement with the wire and thence the wire is carried back to the starting point side of the sash and so on, back and forth between the sash rails.

The other connections of the wire with the sash being substantially the same as those described; I will indicate them by the same reference numerals. A plate 13 is secured to the sash 6 at the opposite end of the frame from the plate 12 and a conductor 14 leads from this plate through a switch 15 to the socket 8. When, therefore, an electric current plug is applied to the socket 8, the circuit will be closed through the conductor 9 and around through the resistance wire or coil 10 which lies adjacent to the surface of the glass back and forth over the glass to the plate 13 and thence to the conductor 14 and the switch to the plug. The circuit may be opened or closed at any time by the operation of the switch. When this current is turned on, the resistance coil will be heated sufficiently so that the radiation therefrom will warm the glass and prevent the ice or snow from clinging thereto and will also dry any moisture resulting from condensation which may be adhering to the outer surface of the glass. The stretches of this resistance coil may be as

near together as seem desirable to produce the best results and it may, of course, be carried back and forth lengthwise of the sash instead of up and down, if preferred, 5 and in various ways its arrangement of the sash may be modified.

To protect the hooks and the supporting plate thereon, I prefer to provide outer guard plates 16 which cover the hooks and 10 the ends of the resistance coil connected therewith and between the inner plates and concealing the wire I provide shields 17 consisting preferably of thin metallic bars semi-circular in form, having their ends 15 brazed to the supporting plates on the sash and partially encircling the coil. These guards serve as a means for protecting the coil from injury or breakage and also serve 20 as deflectors for directing the heat waves upon the surface of the glass.

I prefer to mount the guards in the manner shown and in the form described, but various modifications therein will suggest themselves to any one skilled in this art.

25 The main purpose of the invention is to provide a means for mounting a resistance coil so that the heat therefrom will warm the surface of the glass and dry off the

moisture thereon or prevent the accumulation of ice or snow.

30

I claim as my invention:

1. The combination, with a window sash, of plates secured to the opposite rails thereof and having hooks thereon, a resistance wire engaging said hooks and extending 35 across the glass from one side of the sash to the other, guards mounted on said plates on the outer side of said resistance wire and concealing and protecting the same, conductors connected with said plates, a socket for 40 an electric plug mounted on said sash and in circuit with said conductors, and a switch for directing the circuit through said conductors.

2. The combination, with a window sash, 45 of plates mounted on the side rails thereof and having hooks thereon arranged in staggered relation on the opposite rails, a resistance wire strung between said hooks and lying close to the surface of the glass, suitable 50 guard plates for said resistance wire and conductors for an electric circuit connected with the ends of the wire.

In witness whereof, I have hereunto set my hand this 15th day of January, 1919.

ABRAHAM A. FAGEN.
